(57) **CLAIM**

The ornamental design for a holder for a hand-held electronic communication device, as shown and described.

DESCRIPTION

FIG. 1 is perspective view of a holder for a hand-held electronic communication device, embodying the present invention;

FIG. 2 is a front view of the holder;

FIG. 3 is a bottom end elevational view of the holder;

FIG. 4 is a top end elevational view of the holder;

FIG. 5 is a back view of the holder; and,

FIG. 6 is an elevational view of one side of the holder, the opposite side elevational view being a mirror image thereof. The nature of the article in which the design is embodied is that of an ergonomic holder for hand-held ambidextrous use, for shoulder support, and for underlying surface support; and the intended use of the article is for mounting of an electronic communication device.

The broken lines in the drawings depict environmental subject matter only and form no part of the claimed design.
